(57) **CLAIM**

The ornamental design for an electronic card, as shown and described.

DESCRIPTION

This application incorporates by reference International Design patent application Ser. No. 35/001,284. All the material from the International Application which is essential to the claimed design is included in this application. It is understood that any material in the International Application which is not present in this application forms no part of the claimed design.

FIG. 1 is a front perspective view of the electronic card showing our new design;

FIG. 2 is a rear perspective view thereof;

FIG. 3 is a top view thereof;

FIG. 4 is a bottom view thereof;

FIG. 5 is a right side view thereof;

FIG. 6 is a left side view thereof;

FIG. 7 is a front plan view thereof; and,

FIG. 8 is a rear plan view thereof.
